WASHINGTON LIBBEY EATON, OF HOLYOKE, MASSACHUSETTS.

PRACTICE GOLF BALL.

Application filed May 4, 1922. Serial No. 558,413.

To all whom it may concern:

Be it known that I, WASHINGTON LIBBEY EATON, a citizen of the United States, residing at Holyoke, county of Hampden, and State of Massachusetts, have invented a new and useful Improvement in Practice Golf Balls, of which the following is a specification.

This invention relates to practice golf balls, more particularly to a type of ball which may be used either indoors or outdoors. It is especially adapted, however, for use where distances are limited or where one desires to avoid losing the ball or injuring objects such as windows in adjacent buildings, or the furnishings in a building in which it may be used.

The object of this invention is to provide a practice golf ball simulating as far as possible a regulation ball, but so constructed as to travel a limited distance; and at the same time to provide the mental hazard of the regulation ball, in appearance and manner of flight, though falling short in distance.

An object of the invention is to provide a ball made of resilient material, such as gutta-percha, rubber, celluloid, wood, or treated paper which resembles in size and general appearance a golf ball, but which, on account of its construction, will travel a considerably less distance than a standard ball.

Another object of the invention is to provide such a ball with suitable means, such as holes therein, to render the ball sluggish. This is for the purpose of making it impossible to drive the ball more than a short distance.

The accompanying drawings show for purposes of illustration five of the many embodiments in which the invention may take form. In these drawings, Fig. 1 is an elevational view of a ball having square holes in the outer wall of the ball;

Fig. 2 is a section taken on the line 2—2 of Fig. 1; and

Figs. 3, 4, 5 and 6 are sections showing modified forms of ball.

The ball 4 illustrated in Figs. 1 and 2 is preferably a hollow ball of the same size as a standard golf ball. The walls 5 of the ball are made fairly thick in order that the ball will be strong enough to stand up under the usage to which it is to be put. The outer side of the ball is shown as being roughened

by means of parallel ridges 6, but it is of course obvious that the roughening might be omitted or that it might be in the form of pimples or dimples, or any of the other configurations commonly used on regular golf balls.

The wall 5 of the ball is provided with a large number of apertures 7 which so change the properties of the ball that, when it is hit, it does not travel far in response to the blow. In Figs. 1 and 2 the apertures 7 are shown as being square holes. These holes so disturb the air currents about the ball that very high air resistance is brought about, thereby causing the ball to fall short.

According to the modification shown in Fig. 3, the wall 5 of the ball is provided with a plurality of round apertures 8. It is, of course, obvious that many shapes of apertures other than square or round could be used for the purpose indicated.

Fig. 4 illustrates a modified form of ball in which a central core 9 of suitable material supports by means of a plurality of plugs 10 an outer wall 11. This outer wall is provided with holes 12 similar to the holes above described. The ball is also illustrated as having a dimpled outer surface.

The form of ball shown in Fig. 5 has a solid core 13 while the surface of the ball is provided with exaggerated pimples 14. These pimples are distributed all over the surface of the ball. Between them they provide holes or apertures thereby roughening the surface of the ball to such an extent that its flight is retarded on account of increased friction.

The ball shown in Fig. 6 is also a ball having a solid core 15. It is also provided with a plurality of holes or apertures 16 which project inwardly from the surface of the ball.

Balls such as have been described are particularly well adapted for use as a practice golf ball. They are made the same size as the regulation ball and therefore a player desiring to practice may use one of these balls with his regular golf clubs and may therefore address the ball in the usual fashion. He can practice swinging the club, hitting the ball, and use any of the various clubs he desires without driving the ball a great distance. Practice can be carried on in any suitable place where it is desired, whether it be from a regular tee, in the yard, or indoors, without the likelihood of

losing the ball, injuring by-standers or surrounding objects. The ball is made in such a manner that it is retarded, and therefore does not travel far.

5 It is understood that such a ball could be used in places and at times where the use of a regular ball would be impractical. One could drive out a large number of balls with little danger of loss or damage, inasmuch 10 as the retrieving of them is a comparatively easy matter. Caddying may be avoided.

What is claimed is:

1. A golf practice ball, said ball being hollow in construction, of substantially the 15 same size as the balls employed in the usual golf game, and being provided with nu-

merous apertures communicating with the interior of the ball, said apertures being of a size such as not to materially detract from the rotundity of the ball.

20

2. A golf practice ball, said ball being hollow in construction, of substantially the same size as the balls employed in the usual golf game, the outer surface of the said ball being provided with numerous openings 25 whereby said ball is caused to collapse upon being struck by a club so as to materially reduce the initial velocity imparted to it, and to permit the rush of air through the ball so as to cause the ball rapidly to lose its initial velocity.

30 WASHINGTON LIBBEY EATON.
